UNITED STATES PATENT OFFICE

WILLIAM L. KRUMM, OF CHICAGO, ILLINOIS

DESIGN FOR A BOX

Application filed November 16, 1929. Serial No. 33,474. Term of patent 7 years.

To all whom it may concern:

Be it known that I, WILLIAM L. KRUMM, a citizen of the United States, and resident of Chicago, in the county of Cook and State of Illinois, have invented a new, original, and ornamental Design for a Box, of which the following is a specification, reference being had to the accompanying drawing, forming a part thereof.

I claim:

The ornamental design for a box substantially as shown.

Signed at Chicago, in the county of Cook and State of Illinois, this 31st day of October, A. D. 1929.

WILLIAM L. KRUMM.
